FREDERICK D. W. SEARING, OF NEWARK, NEW JERSEY

STABILIZING DEVICE

Application filed January 6, 1930. Serial No. 418,769.

This invention relates to stabilizing devices and more particularly to self-leveling bases for supporting various articles, instruments and furniture on bodies exposed to pitching and rolling, one of the objects being to furnish a structure or base adapted to support some device practically free of the rolling and pitching movements of the body which carries it. The invention is especially applicable to devices for supporting furniture and appliances used by persons traveling on shipboard.

In the accompanying drawings one practicable embodiment of the invention is illustrated in which drawings,

Figure 1 shows a longitudinal section of my improved base, the base being especially designed in this instance for supporting a chair, the latter being shown in side elevation.

Fig. 2 is a top view of the frame illustrated in Figure 1, the lower portions only of the chair legs being shown to indicate their position, and

Fig. 3 is a section taken at about the plane of the line 3—3 of Fig. 2.

A base made in accordance with my invention may be designed for supporting any selected article of furniture or equipment. In the illustration the base is designed to be supported by the deck or other floor of a ship, and to support a steamer chair, a conventional form of chair being illustrated and furnished with a pair of front legs 5 and a pair of rear legs 6.

The base illustrated comprises a main or outer frame preferably formed of channel iron and having side members 7 and end members 8. In some instances it may be desirable to raise the frame from the surface upon which it rests, and for this purpose legs 9 are shown which for convenience of storage may be pivoted as at 10 to brackets 11 dependent from the side members 7, the upper ends of the legs being held in operative position by engagement with suitable pins 12. This frame, resting as it does on the deck or other part of the boat, is adapted to partake of the movement of the body by which it is carried.

The main purpose of this invention is to permit the portion of the frame which car-

ries the article which is to be stabilized or levelled to have a controlled or damped universal movement, which is the result of portions of the base structure rolling under the piece of furniture, as for instance the chair, in two crosswise directions. In the structure illustrated there are two pairs of curved supports, and two pairs of substantially flat tracks upon which the supports rest. One pair of tracks is shown carried by the outer frame and comprises a longitudinally extending bar 13 having its front and rear ends 14 bent up and passing over the front and rear channel bars 8, and shown secured in position by means of bolts 15. There is shown located upon the bar 13 a strip of wood 16, and upon this a strip of flexible material 17, preferably rubber. These two parts, 16 and 17, constitute in the present illustration a cushioned track, there being one of these disposed at each side of the main frame. Preferably, when the device is to carry some structure such as a chair, these tracks are disposed toward the front, the position being dependent upon the location of the center of gravity of the weight to be carried or stabilized.

Within the main frame there is shown an intermediate frame also formed of channel iron, there being side members 18 and end members 19. A pair of longitudinally curved supports is shown dependent from the intermediate frame and resting on the tracks carried by the main frame. In the present instance each of these curved supports comprises a wooden portion 20 fastened to the side members 18, which may conveniently be done by means of wood screws 21. The supports are made sufficiently long and of proper curvature to accommodate the severest rolling and pitching of a vessel while at sea. The centers of curvature of the supports are, in the illustration, on a line disposed toward the front of the frame, and the centers of the parts 20 are also located forward on the frame.

To prevent longitudinal displacement of the supports they are provided with tapered hobs 22 preferably set widely apart and adapted to sink into preformed sockets 23 in the cushion member 16.

The intermediate frame carries a pair of tracks disposed in a direction transversely or crosswise of its curved supports 20, these tracks being mounted on cross bars 24, the ends 25 of the bars being bent up and around side rails 18 of the intermediate frame and secured in position as by means of bolts 26. The construction of these tracks is practically the same as that for the tracks carried by the main frame and embodies strips of wood 27 secured to the cross bars 24, and resting upon the wooden strips 27, there are also shown rubber cushions 28.

Brackets 30 and 31 are suspended from the front and rear bars of the inner frame for supporting front and rear legs 5 and 6 of the chair.

Within the intermediate frame is disposed the inner frame preferably formed of heavy bars or pipe, there being longitudinal bars 32 at the sides, and cross bars 33 at the ends.

The second pair of curved supports are attached to the inner frame. In the present illustration cross bars 34 are secured, as for instance by bolts 35, to the cross bars 32. The supports are substantially the same in construction as the longitudinally curved supports, and are formed of boards 36 fastened by means of wood screws 37 to the cross pieces 34, and provided with hobs or pins 29 for entering preformed sockets in the cushion 28 of the track carried by the intermediate member.

Soft elastic material, such as the cushions 17 and 28 which face the tracks, when interposed between the curved surfaces of the supports 20 and 36 and the tracks which engage and roll across them, serves to dampen and modify the relative movement of the parts, and also to prevent free oscillation of the frames associated with these curved supports. Curved steadyng and guiding plates 56 are carried by the boards 36 for engaging the sides of the track, preferably the metal bars 34.

The side bars 18 of the intermediate frame carry upstanding posts 38 located in a predetermined position in relation to the center of gravity of the load to be supported. From each of these posts there extends frontwardly and rearwardly a cord 39 passing over a pulley 40 mounted on the side bar 7 of the main frame, and thence to one end of a coiled spring 41, the other end being fastened to a pin 42 also carried by the side bar 7. I have demonstrated that the action of a coiled spring on a part which it controls is materially modified by connecting the spring to the part by means of a cord passing around a pulley.

Posts similar to those carried by the intermediate frame are carried by the front and rear members 33 of the inner frame. These posts are represented by the reference characters 43 and are preferably located on a line

passing through the center of the device. From the posts there extends toward each side a cord 44 passing over a pulley wheel 45 carried by the intermediate member. From thence to one end of a coiled spring 46, the other end of the spring being fastened to a pin 47 carried by the intermediate member.

Suitable safety devices may be employed for preventing overthrow, such as chains 48.

In case additional dampening of the oscillation of the parts is desired, the curved supports, 20 and 36, may be connected by means of cords 49 running over pulleys 50 to coiled springs 51. The dampening effect of this arrangement may be predetermined by selecting the location of the point of attachment of the cord 49 to the support relatively to the center of the support, and by selecting the initial tension of the spring.

When tubing is employed for the inner frame its weight may be increased by filling the tubes with some heavy substance, such as sand 52.

When my improved structures are employed for stabilizing or levelling articles of furniture which are not of a permanent structure in the boat, as for instance when supporting deck chairs, it is often found desirable to remove the chairs from the base and stack them in a well known manner, and to also stack the bases themselves. As the framework is necessarily heavy, I propose mounting at one end of the outer frame rollers to assist those whose duty it is to remove and replace the device.

Wheels 53 are shown mounted on the bent over ends 57 of axles which are shown pivoted to the outer frame, clips 55 being shown secured to the frame part 13 and embracing the axle. The extreme ends of the bent over portions 57 of the axles rest against the frame part 13 for supporting the weight when the wheels are in the full-line positions shown in the drawings. The axle may be turned and the free ends brought against the frame part 14, as in the dotted line position of Figure 1. The wheels may be maintained in this position by catches 58. By this improved wheel mounting the wheels may be housed safely out of the way after the device has been set up on the deck or after it has been removed to a place of storage.

As the invention is illustrated in connection with a deck chair, terms of the deck chair are used in the description of the operation.

When the main frame is supported upon the deck by means of the feet 9, this main frame partakes of the motion of the boat in its rocking and pitching. The chair bearing the weight of the occupant is, however, stabilized by the universal movement occasioned by the tracks rolling under the curved supports, which are disposed in two crosswise directions.

Assuming that the front end of the main

frame in Figure 1 is lowered by the lowering of the boat in that direction, the track represented by the reference characters 16 and 17 rolls under the longitudinally curved supports 20, this movement being slightly damped by the cushions 17 and by means of the posts 38 and the spring connections. At the same time the sidewise movement imparted by the boat going down at one side of the 5 chair, as for instance at the right-hand side in Fig. 3, the intermediate frame rolls under the transversely curved supports 36 without imparting the crosswise movement of the boat to the chair, this relative movement in 10 this instance being also somewhat modified by the cushions 28 and by means of the posts 43 acting through the cords 44 on the springs 46, and by the cords 49 acting on the springs 51.

20 The posts 38 and 43 and the associated springs have a tendency to restore the inner frame to initial position in both directions.

The stabilizing or self-leveling of the inner frame and the chair carried thereby is 25 largely effected by the weight of the inner frame, its weight preventing it from partaking of the movement of the boat. For as the boat moves in either direction and causes the tracks to roll under the curved supports, 30 the leverage in the opposite direction becomes greater due to the weight and to the movement of the balance point or center of gravity. When the inner frame is hollow the leverage may be regulated by adding to or removing 35 from the heavy filling material.

Although the form of my invention selected for illustration is intended for supporting a deck chair, yet it is to be understood that the invention is applicable to supports for other 40 articles used on shipboard, and that various changes may be made as occasion demands within the scope of the claims without departing from the spirit of my invention.

Having described my invention, I claim 45 and desire to secure by Letters Patent:

1. The combination with an outer frame and a pair of longitudinally disposed tracks carried thereby, and elastic material facing the tracks, of an intermediate frame, a pair 50 of longitudinally curved supports dependent therefrom and supported on the tracks carried by the outer frame, a pair of transversely disposed tracks carried by the intermediate frame, and elastic material facing the tracks, 55 an inner frame and a pair of transversely curved supports dependent therefrom and supported on the tracks carried by the intermediate frame.

2. The combination with an outer frame 60 and a pair of longitudinally disposed tracks carried thereby, and elastic material facing the tracks, of an intermediate frame, a pair of longitudinally curved supports dependent therefrom and supported on the tracks carried 65 by the outer frame, a pair of transversely

disposed tracks carried by the intermediate frame, and elastic material facing the tracks, an inner frame and a pair of transversely curved supports dependent therefrom and supported on the tracks carried by the intermediate frame, the elastic material facing both pairs of tracks serving to dampen and modify relative movement between the tracks and the respective curved supports. 70

3. The combination with an outer frame 75 and a pair of longitudinally disposed tracks carried thereby, and elastic material facing the tracks, of an intermediate frame, a pair of longitudinally curved supports dependent therefrom and supported on the tracks carried by the outer frame, a pair of transversely disposed tracks carried by the intermediate frame, and elastic material facing the tracks, an inner frame and a pair of transversely curved supports dependent therefrom 80 and supported on the tracks carried by the intermediate frame, the elastic material facing both pairs of tracks serving to dampen and modify relative movement between the tracks and the respective curved supports, 85 the elastic material facing both pairs of tracks serving to dampen and modify relative movement between the tracks and the respective curved supports, and spring means active between the outer and the intermediate 90 frames, and between the intermediate and inner frames and serving to dampen relative movements between the respective frames and to restore equilibrium and to limit the amplitude of the relative movements. 95

4. The combination with an outer oblong frame and a pair of tracks carried thereby and disposed longitudinally thereof, of an intermediate oblong frame, a pair of curved supports dependent therefrom and disposed longitudinally thereof and supported on the tracks carried by the outer frame, and a pair of tracks carried by the intermediate frame and disposed transversely thereof, an inner oblong frame and a pair of curved supports 100 dependent therefrom and disposed transversely thereof and supported on the tracks carried by the intermediate frame, a post upstanding from the median part of each side of the intermediate frame, a pulley wheel 105 mounted adjacent each end of each side of the outer frame, an extension spring secured adjacent each end of each side of the outer frame, and cords extending from the posts and each passing about a pulley wheel at one end of the outer frame and connected to the extension spring at the other end of such frame, and posts upstanding from the median part of each end of the inner frame, a pulley 110 wheel mounted adjacent the end of each end of the intermediate frame, an extension spring secured adjacent each end of the ends of the intermediate frame and cords extending from the posts and each passing about a pulley 115 at one end of the intermediate frame. 120

5. The combination with an outer frame 125 and a pair of longitudinally disposed tracks carried thereby, and elastic material facing the tracks, of an intermediate frame, a pair of longitudinally curved supports dependent therefrom and supported on the tracks carried by the outer frame, a pair of transversely

and connected to the extension spring at the other end of such frame.

5. The combination with an outer oblong frame and a pair of tracks carried thereby and disposed longitudinally thereof, of an intermediate oblong frame, a pair of curved supports dependent therefrom and disposed longitudinally thereof and supported on the tracks carried by the outer frame, and a pair 10 of tracks carried by the intermediate frame and disposed transversely thereof an inner oblong frame and a pair of curved supports dependent therefrom and disposed transversely thereof and supported on the tracks carried by the intermediate frame a pulley 15 wheel mounted on each side of the outer frame, an extension spring also secured to each side of the outer frame, and cords secured to each side of the intermediate frame 20 and passing about the pulley wheels on the outer frame and connected to the extension springs on such frame, a pulley wheel mounted on each end of the intermediate frame, an extension spring also secured to the end of 25 the intermediate frame and cords secured to each end of the inner frame and passing about the pulleys on the intermediate frame and connected to the extension springs on such frame.
- 30 6. In means for stabilizing ship's furniture, the combination with a frame and a pair of curved supports dependent therefrom, of a second frame, a pair of tracks carried thereby and underlying the curved supports of 35 the first named frame, pulley wheels mounted on the second frame and extension springs also secured to such frame, and cords secured to the first named frame and passing over the pulleys and connected to the extension 40 springs.

Signed at New York, N. Y. this fourth day of January, 1930.

FREDERICK D. W. SEARING.
